ABSTRACT OF THE DISCLOSURE

In a gas cooling turbo-generator, the rotor has cooling channels in the winding slots and slot insulation at the slot surfaces, with a bundle of conductors arranged in each slot. The stator core has radial air gaps opening into the air gap for conducting coolant. The coolant channels in the winding slots have inlet and outlet openings. Each bundle of conductors is formed of mutually insulated solid conductors glued together, the bundles being separated from the slot insulation by spacer elements arranged consecutively axially and limiting in the axial direction slot cooling channels formed between the conductor bundles and the slot insulation.

BACKGROUND OF THE INVENTION

30

 (1) *Field of the invention*

The present invention relates to a turbo-generator with inlet and outlet openings for cooling channels in the winding slot of the rotor opening into the air gap. A gaseous coolant is forced in known manner through the inlet opening into the air gap by means of over-pressure arising due to the movement of the rotor in relation to the surrounding air, for example due to oblique positioning of the openings. Similarly cooling gas is sucked out of the outlet openings facing the air gap.

 (2) *The prior art*

In known machines of similar type the insulation between said bundles of conductors and the walls of the slot consists substantially of a thick insulating casing tightly enclosing the bundle of conductors and holding it together. In order for the relatively low pressure difference between the inlet and corresponding outlet opening to be able to force a sufficient quantity of cooling gas through the slot, this must be cooled by means of several cooling circuits and each cooling circuit must be so designed that the flow distance from the inlet opening to the outlet opening is relatively short. In known modern machines with air gap intake, the cooling channels are arranged diagonally in relation to the bundle of conductors so that the cooling gas flows in through holes in the slot, is led on one side of an axial plane through the centre of the slot down to the bottom of the slot and then back to the air gap through cooling channels arranged on the other side of said axial plane. The inlet opening is situated in a zone limited in axial direction where cooling gas is supplied to the air gap by means of radial channels in the stator and corresponding outlet openings are situated in a zone axially apart in which the cooling gas flowing from the slot is sucked into the stator core.

It is known to provide cooling channels running in the slot with the help of spacer elements of corrugated sheet metal between the slot wall and the bundle of conductors, whereby the ridges formed in the metal run in axial direction. However, this construction necessitates a thick layer of insulation between the bundle of conductors and

2

the corrugated metal and is scarcely suitable since effective cooling can only be achieved if those conductor surfaces past which the cooling gas flows are uninsulated, or at the most insulated with a very thin layer with rather small heat insulating capacity.

According to a more recent, known construction, the cooling channels in the rotor are made by punching holes in the various conductors in a conductor bundle in such a way that a certain axial displacement of cooperating holes takes place between adjacent conductors. The main insulation between the bundle of conductors and the core consists of a thick coil insulation which surrounds the bundle and keeps the conductors together.

According to another known, rather recent version, 15 diagonal slots are made in the side surfaces of the bundle of conductors, for instance by milling, which slots, together with the coil insulation surrounding the bundle of conductors, form walls in the diagonally running channels.

Both the latter constructions provide effective cooling but have the disadvantage that the manufacturing process is so complicated and time-consuming that a great part of the advantage gained in the form of more economical use of material since high-pressure fans are not required is counteracted by an increase in manufacturing costs.

SUMMARY OF THE INVENTION

The above disadvantages are avoided by means of the invention which relates to a gas cooled turbo-generator comprising a rotor having winding slots furnished with cooling channels and slot insulations abutting the slot surfaces, and a bundle of conductors arranged in each slot, and a stator surrounding the rotor, the stator core having radial channels opening into the air gap, said channels being for the supply and removal of a gaseous coolant for directly cooling said bundle of conductors, while the coolant channels in the winding slots of the rotor are provided with inlet and outlet openings, known per se, for pressure or suction action, respectively, and is characterised in that said bundle of conductors consists of mutually insulated solid conductors glued together and that said bundle of conductors is separated from the walls of the slot by means of several spacer elements of insulating material arranged axially consecutively and abutting the slot insulation, in which said spacer elements in axial direction at least partly limit a number of first and second slot cooling channels arranged in axial sequence and formed between the conductor bundle and the slot insulation, and that said first slot cooling channels are in connection with the inlet openings and said second slot cooling channels with the outlet openings, said first and second slot cooling channels being connected in pairs with each other and that said spacer elements are glued to the side surfaces of the bundle of conductors and that the only or substantially solid insulation between the core and the side surfaces of the conductor bundle not covered by said spacer elements consists of said slot insulation.

In a turbo-generator according to the invention great use has been made of the fact that with modern glue and adhesion processes it is possible to effect extremely reliable mechanical connections between metal surfaces and between metal and non-metallic substances. Experiment has led to the conclusion that by means of internal gluing of the conductors a conductor bundle in a turbo-rotor obtains such great rigidity that most of the surfaces facing the slot walls may be without support against the slot walls, assuming that the spacer elements between the conductor bundle and slot walls are glued to the conductor bundle so that they with certainty retain the correct position during the action of centrifugal forces and

during movement caused by alterations in temperature. By exploiting this fact in a machine according to the invention the cooling channels in the rotor slot can be shaped in such a way that they are suitable for a rotor with air gap intake since the total channel cross section will be relatively large while at the same time an acceptable value is maintained for the copper filling factor of the slot. Since the parts of the conductor bundle between said spacer elements do not require a casing to keep them together, and since the slot insulation is dimensioned to provide at least the main part of the solid insulation of the conductor bundle from the core, the copper surfaces not covered by the spacer elements have direct contact with the cooling gas flowing past, or contact through a thin layer, for example a layer of varnish, having rather small heat conducting capacity.

In a turbo-generator according to the invention the rotor winding can be manufactured with very low manufacturing costs in comparison with known turbo-rotors with air gap intake, since the conductors can be made with solid, rectangular cross section, without punching or milling.

BRIEF DESCRIPTION OF THE DRAWINGS

In the following the invention will be described with reference to the accompanying drawings where FIGURE 1 shows an axial section through a turbo-generator according to the invention and illustrates the general principle for a generator with air gap intake. The flow direction of the coolant is shown here, as well as in the other figures, with the help of arrows. FIGURE 2 shows an axial section through the winding slot of the rotor; FIG. 3 shows the winding slot and the wound conductor bundle in radial view, elements lying radially outside of the conductor bundle and spacer elements being omitted; FIG. 4 shows in radial view a part of the radial surface; FIG. 5 and FIG. 6 show the cross-sections on the lines B—B and C—C, respectively, of FIG. 2.

FIGURES 7, 8 and 9 show the shape of the cooling channels in another embodiment of the invention. FIGURE 7 shows a radial view of a rotor slot with conductor bundle and spacer elements with the slot wedge and the insulation inside removed. FIGURE 8 shows an axial section along the line D—D in FIGURE 7 and FIGURE 9 shows the slot in cross section along the line E—E in FIGURE 8.

Another embodiment is shown in FIGURES 10, 11, 12 and 13, where FIGURE 10 shows a winding slot in radial view with the slot wedge removed. FIGURES 11 and 12 show axial sections along the lines G—G and H—H, respectively in FIGURE 10. FIGURES 13 and 14 illustrate details of the insulation.

In FIG. 1 the rotor is designated 1 and the stator 2. Cooling gas flows from the inlet frames 3 radially outside the stator through radial channels, not shown in FIGURE 1, to the feeding-in zones in the air gap. The supply openings for cooling channels in the rotor slot are also situated here.

In a corresponding manner radial stator channels lead from outlet zones in the air gap to the outlet chamber 5 radially outside the stator core.

FIGURES 2, 3, 4, 5 and 6 show an embodiment of the invention where said spacer elements are formed by surrounding with large pitch the conductor bundle with a thick, insulating, essentially helical tape wound with a large pitch, the width of which tape is only a fraction of the pitch.

In the drawings 6 designates a rotor slot with slot insulation 7. The slot 6 contains a bundle 8 of conductors which are insulated from each other and internally glued so that the bundle 8 forms a stiff and solid unit.

The necessary insulation for the core is effected substantially by the slot being provided with a strong and effective slot insulation and furthermore by the gap between the bundle 8 and slot insulation 7 being taken up

by insulating spacer elements 9 and cooling channels 20, 22, 25, 26 formed by said spacer elements and having an insulating coolant flowing through them.

The spacer element 9 consists of the parts of a relatively thick, tape-shaped insulation parallel with the walls of the slot, which is wound with a high pitch and surrounds the bundle of conductors 8—shown in FIGURES 2 and 3—and is glued to the conductor bundle. If the centrifugal forces are great it may be suitable to make the helical insulation body of thin, leafed, tape-shaped parts which are relatively short, and arrange ends projecting from these between the conductors in the bundle so that the helical insulating body is anchored. The slot wedge 11 is shaped the same for all slots and is provided with inlet openings 12 and outlet openings 13.

Between the slot wedge 11 and the conductor bundle 8 are several filling bodies 14, having a thickness approximately the same as the thickness of the tape surrounding said conductor bundle. The parts of the tape between the wedge and the conductor bundle are designated 27.

The inlet openings 12 are arranged in pairs in direct connection with a parallelepipedic cooling channel 20 for in-flowing coolant, which channel comprises a space limited between the conductor bundle and the slot insulation of one slot wall and by the tape parts 9 running obliquely along the slot walls. The coolant is also led from the inlet openings 12 through tangentially running distribution channels 21 and into the parallelepipedic space 22 between the conductor bundle and the other slot wall. The space 22 thus also comprises a cooling channel for in-flowing coolant.

The spacer elements 9 are joined to each other at the bottom of the slot by spacer elements 23 consisting of the same continuous tape as the above-mentioned spacer elements. The space between the bottom of the slot and the conductor bundle is consequently divided into several, elongated spaces 24 arranged axially consecutively. These are intended to lead coolant in a transverse direction and in this way form a connection between cooling channels on both sides of the conductor bundle.

The cooling channels 20 and 22 connected to the inlet openings 12 are connected by individual channels 24 to cooling channels 25 and 26, respectively, for out-going coolant, the latter channels also being formed by spaces with oblique parallelepipedic shape and limited in a corresponding way as the channels 20 and 22.

In the embodiments shown in FIGURES 7, 8 and 9 yokes 16 of insulating material are used as spacer elements between the conductor bundle and the slot surfaces provided with slot insulation instead of the above-mentioned insulating tape. The yokes 16 have a rectangular part which is glued to one side of the conductor bundle 8 and a triangular part 18 which is glued to the other side. An intermediate, trapezium-shaped part 19 forms the spacer element between the conductor bundle and the slot bottom. Contrary to the embodiments of the invention shown in FIGURES 2, 3, 4, 5 and 6 the coolant flowing in through a supply opening 12 is not distributed on both sides of the conductor bundle between the inlet opening 12 and the bottom of the slot. After the flow of cooling air has passed the connection channels in the bottom of the slot formed between the yoke parts 19, it flows out through the outlet openings 13. The cooling channels connected to the inlet openings 12 are situated only on one side of the slot and those connected to the outlet openings 13 are situated only on the other side of the slot.

The embodiment shown in FIGURES 10, 11 and 12 differ from those described above since the coolant flows through the coolant channels of the slot without passing from one side to the other of the slot. In the same way as in FIGURE 3 the symbol $\otimes$ designates an inlet opening and the symbol $\odot$ an outlet opening. As spacer elements between the conductor bundle 8 and slot walls provided with particularly strong slot insulation, tongues

31 of insulating material are used, which tongues are glued to the side surfaces of the glued conductor bundle. The tongues 31 may with advantage be made in one piece with an insulating spacer between the slot wedge and the conductor bundle. A construction element formed in this way can suitably be made of several layers of glass fibre cloth baked in cured resin, each layer being given the shape shown in FIGURE 13, and the tongues 33 are bent before curing to form right angles with the longitudinal part 32 acting as upper insulation of the slot.

When the centrifugal forces are so great that an attachment effected solely by means of glueing the tongues 31 is not considered sufficient, these can be made, as indicated in radial section in FIGURE 14 where 34 designates laps of insulating material in the form of fabric or foil which are held together by means of a plastic material. The laps have different lengths in radial direction and are shaped with folded-in parts 35 which are anchored at various points by pressing them between two adjacent conductors in the conductor bundle 8.

I claim:

1. Gas cooled turbo-generator comprising a rotor having winding slots furnished with cooling channels and slot insulation abutting the slot surfaces, and a bundle of conductors arranged in each slot, and a stator surrounding the rotor, the stator core having radial channels opening into the air gap, said channels being for the supply and removal of a gaseous coolant for directly cooling said bundle of conductors, while the coolant channels in the winding slots of the rotor are provided with inlet and outlet openings for pressure or suction action, respectively, characterized in that said bundle of conductors comprises mutually insulated solid conductors glued together and that said bundle of conductors is separated from the slot insulation by means of several spacer elements of insulating material arranged axially consecutively and abutting the slot insulation, wherein said spacer elements at least partly limit in the axial direction a number of first and second slot cooling channels arranged in axial sequence and formed between the conductor bundle and the slot insulation, and that said first slot cooling channels are in connection with the inlet openings and said second slot cooling channels with the outlet openings, said first and second slot cooling channels being connected in pairs with each other, and that said spacer elements are connected to the side surfaces of the bundle of conductors and that substantially the only solid insulation between the core and the side surfaces of the conductor bundle not covered by said spacer elements consists of said slot insulation.

2. Gas cooled turbo-generator according to claim 1, characterized in that said spacer elements constitute sections of an insulating tape wound helically around said conductor bundle with a pitch which is several times greater than the width of the tape, said first and second

slot cooling channels communicating with each other by means of connection channels formed between the bottom of the slot and the conductor bundle and limited in an axial direction by said tape.

5 3. Gas cooled turbo-generator according to claim 1, characterized in that said spacer elements comprise a plurality of yokes arranged axially consecutively, each of which is glued by one leg to each side of the bundle of conductors, the central part of the yoke lying between the bundle of conductors and the bottom of the slot, said first and second slot cooling channels communicating with each other by means of connection channels axially limited by said central parts.

15 4. Gas cooled turbo-generator according to claim 3, characterized in that the length of one leg of the yoke is substantially equal to the height of the slot, whereas the other leg is considerably shorter and substantially triangular in shape.

20 5. Gas cooled turbo-generator according to claim 1, characterized in that said spacer elements comprise tongues of insulating material arranged axially consecutively between one wall of the slot and said bundle of conductors and several tongues arranged in a similar manner between the other wall of the slot and the bundle of conductors, the tongues having a length which is less than the height of the slot and being glued to the upper part of the bundle of conductors, said communicating slot cooling channels being arranged at the same side of the conductor bundle.

25 30 6. Gas cooled turbo-generator according to claim 5, characterized in that each tongue has several laps of thin insulating material which are glued to each other, several laps in each tongue being shaped with different lengths of their radially oriented parts, and the lower ends of these tongues extending between two adjacent conductors in the conductor bundle.
